VACUUM CLEANING APPARATUS.

1,145,048.

Specification of Letters Patent.

Patented July 6, 1915.

Application filed June 21, 1909. Serial No. 503,397.

To all whom it may concern:

Be it known that we, THEODORE WIEDEMANN and JOSEPH H. TEMPLIN, citizens of the United States, and both residing in the city and county of Philadelphia, State of Pennsylvania, have invented a new and useful Vacuum Cleaning Apparatus, of which the following is a specification.

This invention relates to vacuum cleaning apparatus and more particularly to the type of portable cleaners adapted for removing dust, dirt and foreign material generally from carpets, upholstery fabrics and the like by currents of air and in which the pumping mechanism and its adjuncts are as compactly arranged and as small and light as possible for efficient operation.

In vacuum cleaning apparatus as heretofore constructed it has been proposed to arrange the entire mechanism within a single casing in order that the same may be more readily handled and carried from one place to another, but it has been found in view of the variety of uses to which such an apparatus is adaptable that such a construction is not entirely practical for all the intended purposes, since it is frequently undesirable for the air passing through the apparatus to be laden with dust and dirt which has been removed from the carpets, upholstery or the like, and therefore the single casing construction becomes open to serious objection.

In our present invention we provide an apparatus substantially as compact and transportable as those heretofore devised and wherein the dust laden air is drawn into a receptacle entirely separate and distinct from the casing inclosing the operating mechanism but which may readily be connected thereto, thereby assembling the apparatus into a single unit when used for cleaning purposes.

It is often very desirable to frequently use the mechanism for blowing purposes, such as removing particles of dust and dirt from crevices and places inaccessible to the suction hose or using the air for drying the hair or giving a bed an air bath; in all of which uses it is of course obvious that the blowing of dust and dirt from the machine is highly objectionable.

Where the device is operated solely as a cleaner and the dust collecting receptacle is in attached position, it is desirable to have

the parts so positioned as to immediately divert or conduct the dust laden current of air into the said receptacle or separating apparatus and the location of this receptacle is such that it is immediately and conveniently accessible for the purposes of removal, inspection or repairs, novel means being provided for retaining the dust separating devices adjacent the apparatus, and suitable locking devices being employed which can be readily manipulated so that the several parts of the apparatus can be readily connected or disconnected in accordance with requirements.

It is further desirable that provision be made for employment of a suitable pumping or suction and discharge apparatus in conjunction with a motor having a direct connection thereto which is not liable to easily get out of order and which can be conveniently located so as to be at all times capable of convenient inspection and repairs, if necessary, there being thus formed adjacent the apparatus a vacuum reservoir wherein the discharging devices are located, while in the casing proper there is a pressure reservoir containing the motor and pumping chamber or pump proper, the latter located in the present instance above the said motor.

To the above ends we have devised a novel and simple construction of pumping apparatus which is located intermediate of the motor and its adjuncts and the dust separating devices, whereby the power is applied directly to the suction creating devices without any loss of energy, and provision is further made for enabling any part of the suction or discharge apparatus of equivalent devices to be readily accessible at all times for the purposes of inspection, repairs and renewal.

In order that the cleaner may be as small and light as possible so that it can be easily carried by one person from room to room whereby the motor apparatus can be connected with a lead wire of an electric light current, it is desirable that the motor be placed in the lower portion of the apparatus, thus keeping the center of gravity as low as possible, whereby provision is made for arranging the pumping apparatus, motor and pressure chamber in one casing, while the vacuum reservoir containing the dust cleaning or separating devices for re-

moving the dust and dirt from the dust laden air current is contained in a compact receptacle adjacent the aforesaid casing and adapted for detachable connection therewith.

It further consists of other novel features of construction, all as will be hereinafter fully set forth.

For the purpose of illustrating our invention we have shown in the accompanying drawing one form thereof which is at present preferred by us, since the same has been found in practice to give satisfactory and reliable results, although it is to be understood that the various instrumentalities of which our invention consists can be variously arranged and organized and that our invention is not limited to the precise arrangement and organization of these instrumentalities as herein shown and described.

Figure 1 represents a perspective of a vacuum cleaning apparatus embodying our invention, showing certain of its adjuncts disconnected therefrom. Fig. 2 represents a vertical section of the same. Fig. 3 represents a plan of the apparatus, certain portions being broken away for purposes of illustration. Fig. 4 represents a section on line $x-x$, Fig. 3. Fig. 5 represents a section on line $y-y$, Fig. 2, showing the pumping mechanism and one side of the actuating mechanism therefor, showing the position that the upper suction or inlet valvular elements assume during the upward movement of the lower diaphragm and its adjuncts. Fig. 6 represents a section through the pumping mechanism, showing the position that the upper suction or inlet valvular elements assume during the downward movement of the lower diaphragm and its adjuncts. Fig. 7 represents a side elevation of the motor and pumping chamber. Fig. 8 represents a plan of the same. Fig. 9 represents a perspective of a modified form of our invention. Fig. 10 represents a section on line $z-z$, Fig. 9 of a portion of the modified embodiment of our invention. Figs. 11 and 12 represent details of the connecting device. 50 Similar numerals of reference indicate corresponding parts in the figures.

Referring to the drawings:—1 designates our novel construction of vacuum cleaning apparatus, the same consisting of a casing 2 containing the operating mechanism, and a receptacle 3 for the dust separating devices. The former casing 2 comprises a base portion 5 and an upwardly extending flange 6, the latter being provided with a shoulder 7 upon which rests the outer wall or casing 2, which in the present instance is preferably round or cylindrical, although it will be apparent that the exterior shape or contour of the apparatus may be changed or varied, according to requirements.

In order to permit removal of the base 4 from the casing 2, a number of plates 8 are fixedly secured to the casing at suitable intervals in any well known manner, each of said plates having a screw threaded end 9 adapted to project through a suitable opening in the base 4 and receive a wing nut 10 or the like, whereby access to the interior of the casing may be gained, if desired.

11 designates a plate secured to the casing 2 and having an opening 12 therein so positioned as to align with an opening 13 of the casing 2, which latter serves as an inlet port to the interior of said casing and a source of communication between the receptacle 3 and the casing 2. The plate 11 is provided with angular extensions 14 forming a dove-tailed recess with which a suitably shaped plate 15, secured to the receptacle 3, co-operates, it being understood that an aperture or port 15^x is formed in this latter plate, communicating with the interior of the receptacle 3.

It will be noted that a packing ring or bushing 13^x is located in the opening 13 and preferably projects therefrom sufficiently to contact with the plate 15 and thus insure a tight joint and prevent leakage when the parts are in assembled position.

16 designates a top suitably secured to the casing 2 and having an opening 17 therethrough, forming an outlet port or discharge for the air, which passes through the pumping apparatus and in the present instance this opening 17 has a suitable union 18 mounted therein, whereby attaching devices may be connected, as desired.

19 designates a handle secured to the top 16, said handle being preferably of sufficient length so that when it is desired to transport the apparatus from one apartment or room to another it can be readily grasped by two people, if necessary.

The receptacle 3, which we term the vacuum chamber or reservoir, is provided with an outlet 20 aligned with respect to the openings 13 and 15^x and serving to permit the air passing therethrough to exit to the pumping chamber. As herein disclosed, 21 designates a ring flange fixedly mounted in 115 any well known manner and adjacent the top of the receptacle 3 and serving as a securing means for a protecting screen 22 formed of wire mesh or gauze or the like, and within which is removably secured a 120 dust bag 23. In the present instance this dust bag is provided with a bottom 24 of wood or other suitable material and has its upper end open and provided with a looped portion 24^x surrounding a ring 25 of a diameter substantially that of the interior of the receptacle 3, whereby when the same is placed within the receptacle it will rest upon the flange 21 and hold the dust bag in correct operative position.

26 designates the closure or top of the receptacle 3 and in the present instance is provided with an air inlet port 27 comprising a tubular inclosing member 28 and a 5 deflecting plate 29, whereby a passage is formed which delivers the entering air tangentially to the interior of the casing.

As here shown the top 26 is provided with a locking device consisting of a tongue 30 10 secured by screws 31 or the like to the top 26 and projecting a sufficient distance beyond the edge of said top in order to engage a slot 32 formed in the side of the receptacle 3. A similar slot 33 is formed in 15 the present instance on the opposite side of the receptacle 3 and is adapted to receive a tongue 34, which, as here shown forms an integral part of a crank connection 35 eccentrically mounted upon a handle 36 suitably 20 mounted and guided on the top 26 for ready movement.

It will be apparent that by the employment of the locking device just described the top 26 may be readily disconnected from 25 the receptacle, permitting ready access to the dust bag and its adjuncts. In order to remove the said top 26 it is only necessary to give substantially a half turn to the handle 36, whereupon the eccentric connection 30 removes the locking tongue 34 from engagement with the slot 33, and the top may then be turned upwardly a sufficient distance to withdraw the tongue 30 from its locking position and release the top. 35

Turning now to Figs. 1, 2 and 3, we will in the further description of the apparatus describe in detail the course of the dust laden air current from the time it enters 40 the suction nozzle during its progress through the apparatus.

37 designates the suction nozzle which is adapted to be applied to the surface of the carpet, upholstery or other fabric to be cleaned, the dust laden current of air being 45 conducted through the pipe 38 and the fitting 39, which is adapted to be inserted in the socket or inlet opening 27 of the cover 26, the current of air passing thence through the passage 40 and is discharged into the 50 bag or separating device 23. The current of dust laden air after passing into the bag 23, the construction and manner of removal of which has already been described, passes thence through the outer screen 22 and is 55 drawn to the outlet opening 20, through which it passes by way of the openings 12, 13 and 15 to the interior of the casing 2, thus gaining access via conduit 41 into what we term the pumping apparatus proper. 60 This pumping apparatus comprises a plurality of annular sections 42 and 43, each having outwardly projecting flanges 44, 45 respectively, the same being secured together by suitable bolts 46 or the like, while 65 the sections are supported upon the upper

extremities of four posts 47, the lower extremities of the latter being supported upon the bosses 48 or their equivalents which may be located in proximity to the base of the apparatus.

49 designates a diaphragm which has its outer periphery secured between the flanges 44 and 45, it being apparent that the same bolts or fastening devices 46 which serve to hold the flanges 44 and 45 in adjustable position also hold the outer periphery of the diaphragm 49 in proper position. As will be understood from Figs. 2, 5 and 6, the diaphragm 49 is provided with an annular opening 50, the edge or inner periphery of said diaphragm being securely held between an annulus 51 and a spider 52, the arms of which latter radiate from a hub 53. To this hub 53 is secured a flap valve 54, here shown as comprising a plurality of sections, 85 preferably of leather or the like and of sufficient diameter to completely cover the spider 52 and opening 50, it being noted that the said valve is held in position by a screw 55 or the like engaging the hub 53. Suitable bolts 56 are disposed at intervals about the inner periphery of the diaphragm 49 and hold the same with the plates 51 and spider 52 securely together.

It will be apparent from the construction just described that if the diaphragm 49 is moved upwardly, as shown in Fig. 2, the valve 54 will assume the position shown in Fig. 5, while upon an opposite movement of the diaphragm the arms of the spider 52 100 will prevent movement of the valve 54 in the reverse directions, the position being that indicated in Fig. 6.

57 designates a partition preferably formed integral with the section 42 and 105 provided with a plurality of openings 58 therein forming a spider-like construction, the arms of which emanate from a hub 59, which latter forms with the screw 60 a securing means for a valve 61 of similar construction to the valve 54 already described.

It will be noted that the inlet passage 41 for the dust laden air discharges on the opposite side of the valve 61 from the diaphragm 49 and therefore to separate the suction from the exhaust a top 62 is provided and secured by means of a screw 63 or the like to the hub 59, while the outer edge of the said top contacts with an annular packing ring 64 having a portion suitably located in a recess 65 provided in the wall of the section 42 and it will therefore be apparent that when the screw 63 is firmly secured to the hub 59 the top 62 will compress the packing 64 and prevent escape of 120 air to the pressure reservoir.

66 designates arms which are secured to the ring or spider 52 secured to the diaphragm 49, the said arms 66 being fastened to the heads 68 of the connecting rods 69, 130

which latter terminate in the eccentric strap 70, it being noted that said eccentric strap and connecting rod 69 and head 68 are preferably jointless or made integral or in one piece.

71 designates an eccentric by means of which the eccentric strap and connecting rod are actuated, suitable bearings being located therebetween for the usual purpose.

10 In the present instance we preferably employ a motor 72 of the electric driven type, since the same is capable of being readily coupled to electric light fixtures of usual construction.

15 It will of course be understood that we employ two eccentric straps connecting rods and their adjuncts, as will be apparent from Fig. 2, although it is evident that a single eccentric strap and connecting rod 23 might be employed, if desired. It will also be apparent that we have a direct connection from each eccentric to the diaphragm 49.

20 It will be clear from the description above given that between the diaphragm 49 and the partition member 57 is formed a somewhat enlarged pumping chamber 73, such chamber extending nearly across the casing of the apparatus, while the proportions of this chamber with respect to the area of the 25 adjacent pressure chamber 74 as well as to other correlated parts is such that there will always be a substantially uniform quantity of air forced into the pressure reservoir 74 and discharged from the outlet

30 port 17 so that the speed of the motor will be at all times substantially uniform, irrespective of whether the nozzle 37 is placed against the carpet, upholstery or the fabric to be cleaned, or whether it is withdrawn 35 therefrom and the motor is simply running free, so that the pumping apparatus is simply sucking in air at atmospheric pressure.

40 In Figs. 2, 7 and 8 we have shown the preferred manner of enabling the operator to readily connect the apparatus up with an electric light socket, 75 designating the plug for attachment to a socket of ordinary construction, whereby when the same is connected to the usual electric light fixture and the current is conducted through the flexible connection 76, the motor may be started.

45 It will be noted that we have preferably arranged a cut out switch 77 see Figs. 7 and 8 at a convenient point on the apparatus in order that the same may be controlled directly at the machine in case of a long connection 76 or other reasons.

50 In Figs. 9 and 10 we disclose an embodiment of our invention wherein the vacuum reservoir 3 may be positioned directly on top of the casing 2, in which case it will of course be understood that suitable changes in construction are necessary for 55 proper operation. As here shown, these

changes consist of forming the outlet 20 in the bottom of the vacuum reservoir 3, to which latter the plate 15 is attached and the plate 11 fixedly mounted on the top of the casing 2, it of course being seen that the openings 13 and 12 are properly aligned to form the air passage. In connection with this arrangement a suitable apertured cap 78 is employed to form a retaining box or the like for the packing 13. The outlet 75 opening 17 or exhaust is here shown located in the side of the casing 2.

60 It will be apparent that the angular extensions 14 form a dove-tailed connecting means between the two plates and permit the two receptacles being detachably secured together in a firm and substantial manner and practically sealed by the packing employed. The operation is as follows:—In operating the device the vacuum reservoir 80 3 is first attached to the pump casing 2 by inserting the plate 15 within the extensions 14 and then sliding the two plates together so as to bring the apertures into alignment to permit the passage of air from one to the other. As soon as the fitting 75 is placed in connection with a suitable socket and the switch 77 closed, the current is admitted to the motor, the parts then appearing as seen in Figs. 2 and 9, according whether the 85 vacuum receptacle 3 is at the side or on top of the casing 2.

65 In Figs. 5 and 6 the diaphragm 49 and its adjuncts are seen in the positions they may assume upon the rotation of the eccentrics 71 and it will be evident that the different positions of the parts will rapidly in succession assume the appearance seen in these figures, it being apparent that as the connecting rod 69 moves upwardly they will 100 raise the diaphragm 49 into the position seen in Fig. 5, whereupon the air in the chamber 73 will be compressed and will cause the several diaphragms to assume the positions there indicated, whereupon the air will pass in the direction of the arrows as seen in Fig. 5, downwardly into the pressure chamber 74 and thence to the opening 17 of the atmosphere. A further rotation of the eccentrics 71 will cause the descent of 105 the connecting rods 69, whereupon the diaphragms 49, 54 and 61 will assume the positions seen in Fig. 6 and the air will be drawn in through the perforated spider 57 into the pumping chamber 73, it being understood that as the diaphragm 49 moves from the position seen in Fig. 5 to the position seen in Fig. 6, the parts assume the position seen in said Fig. 6 by reason of the accumulation of pressure in the pressure chamber 74, as will be apparent to those skilled in the art.

70 We have found in practice that the most satisfactory results are obtained from the employment of a motor actuating two 110

cranks or eccentrics, each having a connecting rod connected at one end to or actuated by one eccentric, while the opposite end of each of said connecting rods is rigidly secured to an arm or head 66 attached to the diaphragm 49, the latter being secured at its outer periphery to a suitable fixed point and said diaphragm serving to actuate or to co-act in conjunction with suitable vacuum

10 cleaning devices.

It will now be apparent that we have devised a novel and useful construction which embodies the features of advantage enumerated as desirable in the statement of the 15 invention and the above description and while we have in the present instance shown and described the preferred embodiment thereof which has been found in practice to give satisfactory and reliable results, it 20 is to be understood that the same is susceptible of modification in various particulars without departing from the spirit or scope of the invention or sacrificing any of its advantages.

25 Having thus described our invention, what we claim as new and desire to secure by Letters Patent, is:—

1. In a vacuum pumping apparatus, the combination of a casing having an inlet and 30 an outlet port, means for dividing said casing so as to form a pressure reservoir which is connected with said inlet port and a pumping chamber which is connected with said outlet port, pumping mechanism co-operating 35 with said pumping chamber, and located within said casing, a motor in said casing and driving connections for positively actuating said pumping mechanism from said motor, a self-contained receptacle separate from said 40 casing and located outside thereof, said receptacle forming a vacuum reservoir provided with an inlet port and an outlet port, said outlet port being located adjacent the inlet port of the case, and detachably connected 45 thereto.

2. In a vacuum pumping apparatus, the combination of a casing having an inlet

and an outlet port, means for dividing said casing so as to form a pressure reservoir which is connected with said inlet port and 50 a pumping chamber which is connected with said outlet port, pumping mechanism co-operating with said pumping chamber and located within said casing, a motor located within said casing, driving connections between said motor and said pumping mechanism, a self-contained receptacle separate from said casing, and located outside thereof, said receptacle forming a vacuum reservoir provided with an inlet port and an 60 outlet port, said outlet port being located adjacent the inlet port of the casing, and means for detachably securing the receptacle to the casing with the outlet port of the receptacle in alignment with the inlet port of the casing, said last named means including a packing positioned to prevent leakage between the receptacle and the casing.

3. In a vacuum pumping apparatus, the combination with a casing having an inlet port and an outlet port, means for dividing said casing so as to form a pressure reservoir which is connected with said outlet port, pumping mechanism co-operating with 70 said pumping chamber and located within said casing, a receptacle separate and independent from the casing and located outside the same, said receptacle forming a vacuum reservoir and having an inlet port and an outlet port, said outlet port being located 75 in the side of the receptacle and at substantially the same height as the inlet port in the side of the casing, and means for detachably connecting said receptacle and said casing with the outlet port of the receptacle 80 in alignment with the inlet port of the casing, said means containing a packing for preventing leakage around said connection.
